E. D. COOK

SYNCHRONISM INDICATING MEANS

Filed June 6, 1927

Inventor:
Ellsworth D. Cook,
by *Alvander S. Lunt*,
His Attorney.

Patented Oct. 23, 1928.

1,688,790

UNITED STATES PATENT OFFICE.

ELLSWORTH D. COOK, OF SCOTIA, NEW YORK, ASSIGNOR TO GENERAL ELECTRIC
COMPANY, A CORPORATION OF NEW YORK.

SYNCHRONISM-INDICATING MEANS.

Application filed June 6, 1927. Serial No. 196,800.

My invention relates to means for indicating synchronism between voltages on a plurality of conductors such as those comprising parts of the usual power distribution system and it has for its purpose to provide means which may be economically constructed and which will furnish the desired indication in a reliable and satisfactory manner.

A principal object of my invention is to provide means of the type indicated which dispenses with the use of potential transformers of the usual type and in which the indication may be had by utilizing a synchronoscope of a standard commercial construction, such for example as that shown in Patent No. 1,641,693 to David R. Price and Francis H. Bowman, synchronoscopes, issued September 6, 1927, and which is assigned to the same assignee as the present application.

concentric cylindrical conducting sheaths 6 and 7, and 8 and 9 respectively. The outer sheaths 7 and 9 are located near the inner surface of this bushing and are maintained at ground potential. The inner sheaths are dielectrically separated from the conductors 1 and 2 and from the outer sheaths and have voltages impressed thereon which are dependent in magnitude on the distance of the sheaths from the conductors. These sheaths constitute a capacitance transformer the construction of which has been set forth with particularity in Patent No. 1,657,249 to Eugene D. Eby issued January 24, 1928. The sheaths 7 and 9 are connected together through a conductor 10 and through conductors 11, 12 and 13 to ground potential. The inner sheaths 6 and 8 are connected through conductors 14 and 15 respectively to the grids of the electron discharge devices 17 and 18. The electron discharge devices 17 and 18 and also the electron discharge

A further purpose of my invention is to provide means of the type indicated in which the synchronoscope may be situated at any convenient distance from the conductors the voltage of which is to be synchronized and in which its operation will be substantially unaffected by extraneous fields and disturbances.

30 The novel features of my invention will be set forth with particularity in the appended claims. My invention itself, however, both as to its organization and method of operation together with further objects 35 and advantages thereof may best be understood by reference to the following description taken in connection with the accompanying drawing in which the single figure represents a preferred embodiment of my invention.

Referring to the drawing, 1 and 2 represent conductors upon which are impressed voltages the synchronism of which is to be indicated. These conductors are represented as passing through high tension bushings or insulators 3 and 4 respectively, which may be of the usual oil filled or condenser type such as those which are employed with the usual transformer or oil switch case. 5 represents a synchronoscope of the type set forth in the above mentioned patent and which I employ in connection with my invention. 6 is a high tension lead which connects the conductors 1 and 2 to the synchronoscope 5. 7 is a high tension lead which connects the synchronoscope 5 to the generator 25. The armature of the generator 28 is connected to a circuit including conductor 31, resistance 32 and conductors 12, 13 and 33. Thus the right-hand end of the resistance 32 is at ground potential and the left-hand end is at a potential below ground by an amount dependent upon the source 28. This potential may be varied as desired by means of the resistance 63 connected in series with the field coil of the generator 28. The grids of the electron discharge devices 17 and 18 are connected through resistances 34 and 35 respectively and conductor 26 to an adjustable point upon

Within the bushings 3 and 4 and represented by dotted lines in the drawing are and conductor 36 to an adjustable point upon the resistance 32 thereby providing a suitable 110

negative potential for the grids of these devices. The anode circuits of the devices 17 and 18 are supplied with voltage from the generator 29 through a circuit including conductor 40, primary windings of the transformers 41 and 42, conductors 43 and 44, space between the anode and cathodes of the devices 17 and 18 to the cathodes of these devices and thence through circuit 21 and conductors 11, 12, 13 and 33 to the opposite side of the source of potential 29. Likewise the anodes of the devices 19 and 20 are supplied with voltage from the sources 29 and 30, through a circuit including these sources connected in series, conductors 45, reactors 46 and 47 respectively, spaces between the anodes and cathodes of the devices 19 and 20, to the cathodes of these devices and thence through circuit 22, conductors 11, 12, 13 and 33 to the negative side of the source 29. The grids of the devices 19 and 20 are supplied with biasing voltage through conductors 48 and 49, secondary windings of the transformers 41 and 42 respectively and conductor 50 which is connected to a suitable point on the resistance 32. The output circuit of the electron discharge device 19 is connected through a blocking condenser 50 and conductor 52 to two branch circuits, one including a resistance 53 and one of the coils of the synchronoscope 5 to ground at the point 54, and the other including the inductance 55 and a second coil of the synchronoscope 5 to the point 54. The output circuit of the electron discharge device 20 is connected through a blocking condenser 56, conductor 57, resistance 58 and a separate coil of the synchronoscope 5 to ground at the point 59. The description and operation of the synchronoscope 5 is fully set forth in the above mentioned patent to David R. Price and Francis H. Bowman and, therefore, will not be more fully explained here.

When voltages are impressed upon the conductors 1 and 2, a portion of these voltages will appear between the conducting sheaths 6 and 7, and 8 and 9, these constituting in effect capacitive connections with the conductors 1 and 2. This voltage is impressed upon the grids of the electron discharge devices 17 and 18 respectively through the conductors 14 and 15 and resistances 60 and 61 respectively. The impedance of the input circuit including devices 17 and 18 is very high such that no appreciable current flows through the conductors 14 and 15 and as a result the voltages upon the grids of the devices 17 and 18 bears a substantially constant relation both in phase and magnitude to the voltages on the conductors 1 and 2. This is a particularly important feature due to the fact that if current is allowed to flow in these circuits the phase relation between the voltage on the grids of the devices 17 and 18 and that on

the conductors 1 and 2 may be variable because of this current and as a result the precision of the device will be greatly reduced; or phase compensating means will be necessitated.

For this reason the capacitance transformers constituted by the sheaths 6 and 7, and 8 and 9 are peculiarly adapted to the present purpose. The current which can be drawn from these devices is very small notwithstanding that the impedance of the circuit connected thereto may be relatively low. By making the circuits including the grids of the devices 17 and 18 of high impedance this current can be maintained at such small value that the voltages on the grids of devices 17 and 18 will bear a substantially constant phase relation to the voltage of the conductors 1 and 2 respectively.

The amplified voltages which appear in the anode circuit of the devices 17 and 18 are impressed upon the grids of the amplifiers 19 and 20 through the transformers 41 and 42. The devices 19 and 20 operate as power amplifiers for supplying currents to the synchronoscope 5.

In the design of the apparatus the circuits are so arranged as to minimize the shift in phase of the voltages between the capacitance transformers and the synchronoscope. Such inductance and capacitance units as are necessary are so arranged in the circuits and are of such magnitude that their effects on the phase relations mentioned are minimized. The cathode circuits of the tubes are maintained at ground potential as are also the sheaths 7 and 9 of the capacitance transformers. The tubes 17 and 18 are located in comparatively close proximity, as for example, within a range of fifty feet, or so, to the capacitance transformers. The remaining apparatus may be located at pleasure. By these means distributed capacity effects are minimized and the apparatus is protected against the effects of extraneous fields and influences. For this reason it will be noted that the external sheaths 7 and 9 are somewhat longer than the sheaths 6 and 8 thereby protecting the latter from outside disturbances. With the apparatus as thus constructed the voltages appearing in the output circuit of the devices 19 and 20 will bear the same definite phase relation to the voltage of the conductors 1 and 2 as that which appears between the sheaths 6 and 7, and 8 and 9 and the operation of the device 5 will be as definite as though directly connected to conductors 1 and 2 through potential transformers of the usual type.

The operation of the device 5 is such that if the frequency of the voltage appearing in the system, of which the conductor 1 is a part, is greater than that in the system 2 then the pointer 62 of the device 5 will

gradually move to the right whereas if the frequency of the system 1 is slightly less than that of system 2 then the pointer 62 will gradually move to the left. If the systems 1 and 2 are in synchronism and in phase, the grids of the discharge devices 17 and 18 will be simultaneously positive and negative and likewise the grids of the devices 19 and 20, with the result that the current flowing from the anode of the device 19 through the condenser 50 will be in phase with the voltage of the conductor 2 and likewise the current flowing from the anode of the device 20 through the condenser 56 will be in phase with that in conductor 1, and therefore the pointer 62 of the indicating device will stand at a point on the scale, as at the center, indicating that the systems 1 and 2 are in synchronism and in phase. If the system 1 is in synchronism with the system 2 but in phase opposition then the grid of the device 17 will be positive when the grid of the device 18 is negative, this effect being reflected in the output circuit of these devices and on the grids of the devices 19 and 20 with the result that current flowing in the output circuit of the devices 19 and 20 will likewise be in phase opposition. The needle will then fail to assume the above mentioned center position.

While I have shown a particular means consisting of the capacitance transformers described in the above mentioned patent to Eugene D. Eby for obtaining a suitable connection to the high tension lines 1 and 2 it will be understood that I do not wish to be limited thereto since this is a preferred embodiment and other means may be employed such for example as that disclosed in Patent No. 1,091,722 to V. A. Wolcott of March 31, 1914 consisting of a string of insulators, or other high impedance conducting means, connected between the high tension conductors and ground. Likewise, it will be understood that any suitable type of synchronoscope may be employed.

While I have shown and described a particular embodiment of my invention it will, of course, be understood that I am not to be limited thereto since many modifications, both in the circuit arrangement and in the instrumentalities employed in carrying out my invention, may be made without departing from the spirit and scope of my invention as set forth in the accompanying claims.

What I claim as new and desire to secure by Letters Patent of the United States, is:—

1. In a means for indicating synchronism between voltages on a plurality of conductors, the combination with a synchronoscope, of capacitance transformers associated with each of said conductors and power amplifying means associated with each of said capacitance transformers, said amplifying means being adapted to supply to said

synchronoscope voltages bearing a substantially constant phase relation to the voltage on said transformers.

2. In a means for indicating synchronism between voltages on a plurality of conductors, the combination with a synchronoscope, of capacitance transformers associated with each of said conductors and power amplifying means for supplying alternating current energy from said capacitance transformers to said synchronoscope, the input and output voltages of said amplifying means being in substantially the same phase relation with respect to that of said conductors.

3. In a means for indicating synchronism between voltages on a plurality of conductors, the combination with a synchronoscope, of capacitance transformers associated with each of said conductors, each of said capacitance transformers comprising a pair of conducting cylinders situated concentrically with respect to said conductors, the outer of said cylinders being adapted to protect the inner cylinder from external disturbances and said inner cylinder having voltage impressed thereon from said conductors, and power amplifying means associated therewith for supplying voltage to said synchronoscope bearing a substantially constant phase relation to that on said conductors.

4. In a means for indicating synchronism between voltages on a plurality of conductors, the combination with a synchronoscope, of conducting means located between each of said conductors and ground and electrically separated therefrom, means for protecting said conducting means against outside disturbances, vacuum tube amplifying means adapted to supply voltage from each of said conducting means to said synchronoscope, the cathode circuits of said amplifying means being maintained at ground potential.

5. In a means for indicating synchronism between voltages on a plurality of conductors, the combination with a synchronoscope, of high impedance conducting means situated between each of said conductors and ground and having voltages impressed thereon from said conductors, means for protecting said conducting means from outside disturbances, and power amplifying means associated with each of said conducting means and adapted to supply voltage to said synchronoscope, each of said amplifying means having input circuits of sufficiently high impedance substantially to preclude the flow of currents therein and adapted to supply potential to said synchronoscope bearing a substantially constant phase relation to that on said conductors.

In witness whereof, I have hereunto set my hand this 3rd day of June, 1927.

ELLSWORTH D. COOK.
